UNITED STATES PATENT OFFICE.

ALBERT O. BUCKIUS, OF CHICAGO, ILLINOIS, ASSIGNOR TO THE NATIONAL
MALLEABLE CASTINGS COMPANY, OF CLEVELAND, OHIO.

DESIGN FOR A CAR-WHEEL.

SPECIFICATION forming part of Design No. 24,192, dated April 9, 1895.

Application filed February 5, 1895. Serial No. 537,422. Term of patent 14 years.

To all whom it may concern:

Be it known that I, ALBERT O. BUCKIUS, a citizen of the United States, residing at Chicago, Cook county, Illinois, have invented 5 and produced a new and original Design for Car-Wheels, reference being had to the accompanying drawings, forming a part hereof.

In the accompanying drawings, Figure 1 is a side elevation of my car wheel, partly in section, and Fig. 2 a sectional view, taken on line 2 of Fig. 1.

The leading features of my design consist in a cylindrical hub, flanged periphery and compound curved spokes, which, when viewed 15 in plan view of Fig. 2, present a double concaved appearance.

A is the cylindrical hub portion, provided with an axial opening or perforation *a*; B, the

felly or rim, provided with inwardly projecting annular flanges, *b b*, at each of the 20 peripheral edges, and C the compound curved spokes which join the hub and rim together; and which are somewhat S-shaped in appearance when viewed in side elevation, but which are doubly concaved—as at *c c*—when looked 25 at in a plan view, as shown in Fig. 2—the whole presenting to the eye a harmonious and ornate figure, as illustrated in the drawings.

I claim—

The design for a car wheel herein shown 30 and described.

ALBERT O. BUCKIUS.
